UNITED STATES PATENT OFFICE.

HUIBERT CORNELIS GHIJSEN, OF MIDDDELBURG, NETHERLANDS, ASSIGNOR TO N. V. VITRITE WORKS, OF MIDDDELBURG, NETHERLANDS, A LIMITED LIABILITY COMPANY OF THE NETHERLANDS.

METHOD OF THE MANUFACTURING AND ADJUSTMENT OF CONTACT-PLATES IN SWAN-LAMP BASES.

1,340,041.

Specification of Letters Patent. Patented May 11, 1920.

Application filed April 18, 1919. Serial No. 291,153.

To all whom it may concern:

Be it known that I, HUIBERT CORNELIS GHIJSEN, a subject of the Queen of the Netherlands, residing at Middelburg, Province of Zeeland, in the Kingdom of the Netherlands, have invented certain new and useful Improvements in Methods of the Manufacturing and Adjustment of Contact-Plates in Swan-Lamp Bases, of which

10 the following is a specification.

The invention relates to improvements in the method of the manufacturing and adjustment of contact plates in Swan lamp bases. In applying the new method the 15 two contact plates for one lamp base are placed in a plunger head as one twin plate and in this plunger head are separated one from the other by the strip connecting the two plates being parted in the middle: the 20 portion of the strip left over on each plate is then bent up in the operation of placing the plates on the pins in the mold in which the lamp base is pressed after which in the 25 following phase of the operation the case is placed in the mold and the insulating mass poured in.

The dividing of each twin plate into two halves may, according to the invention be carried out by tearing the connection strip 30 which for this purpose is weakened at or near the middle.

By dividing the contact plates through the tearing of the connecting strip the apparatus for carrying out the operation can 35 be made much simpler and less costly.

On the accompanying drawings an apparatus for carrying out the method according to the invention is represented.

Figure 1 is a longitudinal section through 40 a plunger head with mold.

Fig. 2 is likewise a longitudinal section of the lower portion of the plunger head, taken in a plane at right angles to that of Fig. 1 with the movable core omitted.

45 Fig. 3 is a cross section of the plunger head corresponding to the line A—A of Fig. 2.

Fig. 4 is a cross section corresponding to the line B—B of Fig. 2.

50 Fig. 5 is a cross section corresponding to the line C—C of Fig. 2.

Fig. 6 shows in side elevation the core piece with forked ends.

Fig. 7 is an end view of the forked end of the core piece.

Fig. 8 is a plan view of the blank from which contact plates are formed.

Fig. 9 is a side elevation of the same.

Fig. 10 is a plan view of the finished contact plates.

Fig. 11 is a side elevation of the parts shown in Fig. 10.

The twin contact plates are fed into a plunger head 11 through a guide channel 15 in the holder arm 7 by means of a feeding 65 bar 6 having a reciprocating motion. The plunger head is formed with a side opening 13 for the insertion of the contact plates. The plunger 10 is open on two opposite sides and at its upper end is screwed 70 fast into a spring box 51 inclosing a spring 21 which at its upper end presses against a collar 22 of the core piece 20.

The core piece has at its lower end a two legged fork 24. The spring 21 thus 75 holds the core piece and fork continually pressed upwardly. The core piece 20 with fork 24 has a common axis with the plunger and can move along this axis against the pressure of the spring. The two fork 80 legs 25 the section of which corresponds with the shape of the contact plates work through guide openings in the conical head 12 of the plunger head, these openings having sections corresponding to that of the 85 fork legs. In the lower end of the plunger head there is a small anvil 30 attached by screws 52 and this anvil partially closes the opening in the plunger head. With the downward motion of the fork 24, 25 the 90 fork legs glide on both sides over the anvil. The plunger head is guided in its motion by the bore 9 in the guide box 8.

A mold 16 is placed under the guide box 8 and in the opening 17 in this mold is 95 placed the metal case for the lamp base and insulating mass. Two pins 18 are fixed to the base 19 of this mold on which the contact plates can be placed. The contact plates are formed with holes for this purpose. The small anvil 30 is formed on its upper side with a transverse slit or groove

53 in which the connecting strip rests when the twin contact plate is inserted. This slit insures the plate being in the correct position before the plunger starts on its downward stroke.

In the opening 13 for the insertion of the twin contact plate in the plunger head there are guide plates 54 which are screwed on both sides to the inner wall of the plunger head. On inserting the contact plates the pointed outer ends of these contact plates glide along the guide plates until the contact plates reach the middle of the plunger head in which position the strip is above the slit 53. The contact plate then falls down until the connecting strip rests in the slit in the small anvil.

The guide box 8 is provided at the side where the contact plates are inserted with an inwardly projecting portion 55 in order to insure the passage of the contact plates from the guide channel 15 into the plunger head.

The apparatus works as follows:

25 The twin contact plate is inserted through the guide channel of the apparatus and through the opening 13 in the lowest portion of the plunger head. The plate then lies on the anvil 30 and rests with the strip connecting together the two halves of the contact plate in the slit 53 in the middle of the anvil.

30 On the downward stroke of the plunger the plunger head with the anvil 30 descends to the bottom of the mold the twin contact plate being taken down with it. The holes with which the two halves of the contact plate are provided are thus brought over the pins fixed in the bottom of the mold and the pins thrust through them. The pins are pointed for this purpose.

35 When the plunger 10, 12 comes to rest on the bottom of the mold the core piece 20, 24 still continues its motion downward and

the spiral spring 21 situated in the spring 45 box 51 is thereby compressed.

Two vertical holes are bored in the bases of the fork-legs in positions corresponding to the positions of the two pointed pins in the mold.

50 The fork legs thus move over the mold pins on the downward motion and cause the contact plate to be held.

As the two legged plunger 24 goes further downward the connecting strip tears 55 apart at the thinnest place and the two halves of the strip are bent up against the anvil or bridge piece. The two contact plates are thus placed in their correct positions on the bottom of the mold.

55 After this first the core piece 24, 25 and then the plunger 10, 12 commence their upward stroke and another twin contact plate can be brought along for placing in the following mold.

60 What I claim is:

1. Improvements in the method of production and adjustment of contact plates, which are each in the form of a twin contact plate, the said contact plates are 70 brought into the plunger head and are there split apart, the portion of the connecting strip remaining on each contact plate being bent up against the side of a small anvil provided in the plunger head, the said contact plates being pressed down by a core piece with forked ends movable in the plunger head until pins fixed to the mold, in which the lamp base is pressed pass through holes formed in the contact plates.

75 2. Method according to claim 1 wherein the dividing of each twin contact plate into two parts is effected by the tearing of the connecting strip which for this purpose is weakened at or near the middle.

80 85 In testimony whereof I have hereunto set my hand.

HUIBERT CORNELIS GHIJSEN.
